UNITED STATES PATENT OFFICE.

BENJAMIN B. BETTS, OF ST. LOUIS, MISSOURI.

COMBINED ANTICREEPING RAIL AND TIE-PLATE.

1,240,406.

Specification of Letters Patent. Patented Sept. 18, 1917.

Application filed September 23, 1916. Serial No. 121,853.

To all whom it may concern:

Be it known that I, BENJAMIN B. BETTS, a citizen of the United States, and resident of St. Louis, State of Missouri, have invented certain new and useful Improvements in Combined Anticreeping Rails and Tie-Plates, of which the following is a specification containing a full, clear, and exact description, reference being had to the accompanying drawings, forming a part hereof.

My invention relates to improvements in combined anti-creeping rails and tie plates, and has for its object the construction of a rail and tie plate which conjointly act to prevent creeping of the rails incident to the movements of rolling stock, as well as to prevent relative lateral movements of the plate and rail when the spikes have been partially lifted and as well as to preserve uniformity in the spacing of the ties.

With the above objects in view, my invention consists in certain novel details of the construction and arrangement of parts which will be hereinafter fully, clearly, and concisely set forth in my specification, pointed out in my claims, and illustrated by the accompanying drawings, in which—

Figure 1 is a plan view showing a short length of a rail constructed according to my invention resting upon a tie plate constructed according to my invention, the tie and spikes not being shown.

Fig. 2 is an end elevation of the rail length and tie plate, as shown by Fig. 1.

Fig. 3 is a perspective view of the rail length and tie plate, shown in Figs. 1 and 2.

Fig. 4 is a plan view of a modified form of rail resting upon tie plates of modified form; and

Fig. 5 is a plan view of a rail length constructed according to my invention and as illustrated by Figs. 1, 2 and 3, resting upon a modified form of tie plate, having a fillet shaped to conform with the margin of the rail base flange.

Referring by numerals to the accompanying drawings, 6 designates a rail of ordinary construction, except for the margin 7 of its one rail base flange, which as clearly shown in Figs. 1 and 3 is corrugated, undulated or provided with alternated depressions and projections 8 and 9 respectively.

The reference numeral 10 designates the body portion of my improved tie plate, which is of substantially rectangular oblong shape, the major portion of its uppermost

face constituting a rail seat, extending transversely of the body portion 10, paralleling the minor axis thereof, and upstanding from the uppermost face of the body are the shoulders 11 and 12, which are laterally spaced a distance substantially that of the width of the rail base flanges, so that the tie plate, as a whole, may be easily applied to the rail with the shoulders 11 and 12 in snug contact with the margins of the rail base flanges.

It is to be observed here that the margin of one rail base flange is as common, a straight margin, and that the corresponding or companion shoulder of the tie plate has its margin straight to conform with the straight margin of the said rail base flange, and that the opposite rail base flange is corrugated, undulated or provided with the depressions 8 and projections 9 and further that the corresponding or companion shoulder 12 of the tie plate has its inner margin corrugated, undulated and provided with the depressions 13 and projections 14 to fit the depressions 8 and projections 9 of the rail base flange 7.

Formed through the tie plate and intersecting the shoulders 11 and 12 are the spike openings 15.

Arising from each of said shoulders 11 and 12, and preferably between the spike openings, is an upstanding lug 16, on the shoulder 11, and 17 on the shoulder 12. The projection 14 of the shoulder 12 forms the inside face of the lug 17.

Assuming a number of ties or sleepers to be in position and a plate or chair resting upon each tie, and at each end thereof and a rail constructed according to my improvements, having its one base flange corrugated, undulated or provided with depressions as described, and said depressions in the rail base flange at regular intervals longitudinally of the rail the depressions in the rail base flange form a means for accurately and uniformly spacing the ties and tie plates, for it is obvious that with said depressions at regular intervals longitudinally of the rail, the spacing of the tie plates and ties is greatly facilitated. After the rail has thus been placed upon the plates, spikes are driven through the plates and into the ties, with their heads overlapping the rail base flanges, which spikes serve to hold the plates against movement relative to the ties and the rails against vertical movements relative to

the plates. It will be observed further that by reason of the undulated or corrugated margin of the rail base flange and a like margin of the one shoulder of the tie plate, that with the tie plate securely fastened to the tie the rail is prevented from creeping or lengthwise movements in either direction relative to the tie plate.

By reason of the lugs 16 and 17, I successfully overcome the dangers arising from lateral displacement of the rails from between the upstanding shoulders of the tie plates in the event the spikes have been partially lifted or not driven fully home with their heads in engagement with the rail base flanges and the shoulders of the tie plate.

In Fig. 4 the rail 18 is not continuously corrugated or undulated in its one base flange margin, but instead is provided with depressions 19, which are spaced longitudinally of the rail distances corresponding to the desired spacing of ties (ties from center to center have an average spacing of approximately twenty inches) and in my drawing Fig. 4 I have shown the depressions 19 spaced longitudinally of the rail about twenty inches from the center of one depression to the center of the next adjacent depression. It is to be understood, of course, that I do not wish to be understood as limiting myself to any particular longitudinal spacing of the depressions.

In Fig. 4 the tie plates are in all particulars like the plates illustrated by Figs. 1, 2 and 3 and which I have described in detail.

In Fig. 5 the rail 20 is in all particulars like the rail shown in Figs. 1, 2 and 3, having its one base flange continuously corrugated. The tie plate 21 in this figure of the drawing has its body portion constructed substantially the same as the plates illustrated by the other figures, the difference in structures being that the plate of Fig. 5 has a greater length than the other plates and its shoulders 22 and 23 are spaced distances greater than the width of a rail base flange, in order to provide for the introduction between the one shoulder and the corrugated margin of the rail base flange, an insert or fillet 24 whose lateral margins are shaped to fit the shoulder 23 and the corrugated margin of the rail base. This plate has spike openings 25 intersecting its straight shoulder 22, while its opposite shoulder 23 is imperforate as in the form shown in the other figures and instead there are spike openings 26 through the fillet 24 and through the body of the tie plate removed laterally from the shoulder 23 and in registration with the spike openings in the fillet. While the construction of this rail anti-creeping device is slightly different from the other forms shown, its function is the same.

It is to be observed that the spike openings 26 (as shown in Fig. 5) are spaced from the

70 rail-bearing seat so that a portion of the body of the fillet or the element of the plate constituting the rail shoulder or abutment lies between the spike opening and the margin of the fillet shoulder or abutment, which is engageable by a rail margin resting on the tie plate.

75 By this expedient; that is, by having metal between the spike opening and the margin of the rail base flange, the rail is prevented from wearing the shank of the spike next its head, as is common. It is to be understood, of course, that the spacing of the spike opening from the rail seat allows the head of the spike to rest upon the upper face 80 of the rail base flange. The same effect, that is prevention of "throat-cutting" of the spikes, is accomplished by the arrangement shown in Figs. 1 and 3 where the spike openings 15 are disposed so as to come opposite 85 the crests of the undulated edge of the rail, that is to say opposite the parts of such edge that extend laterally farthest from the longitudinal central plane of the rail. With this arrangement any longitudinal movement of 90 the rail does not tend to shear and cut the spike, because such movement brings opposite the spike a part of the rail flange that recedes from the spike face.

95 Having thus described my invention what I claim as new therein and desire to secure by Letters Patent of the U. S. therefor is:

1. A rail anti-creeper comprising a rail having a continuous straight edge flange throughout its length and a uniformly corrugated flange throughout its length, a tie plate provided with a rail-bearing seat, a rail-bearing shoulder at one end of said tie plate adjacent said seat, a corrugated rail-bearing abutment arranged at the other end 100 of said tie plate adjacent said seat, said abutment provided with spike openings 105 passing therethrough and through the tie plate and disposed at such distance laterally from the longitudinal central plane of the rail that any longitudinal movement thereof 110 will not cause the corrugated edge to engage with the shanks of the spikes; whereby the shank of a spike adapted to be seated in a spike opening is protected from contact with 115 the corrugated edge of the rail flange, thereby preventing shearing of the spike shank by the corrugated edge of the rail flange.

120 2. A rail anti-creeper comprising a rail having a continuous straight flange throughout its length and a corrugated flange throughout its length, a tie plate provided with a rail-bearing seat, a rail-bearing abutment at one end of said plate adjacent said seat and having spike openings formed 125 therethrough, a corrugated rail-bearing abutment arranged at the other end of said tie plate adjacent said rail-bearing seat and provided with spike openings removed from 130 the corrugated edge of said abutment, where-

by the shank of a spike adapted to be seated in said opening is protected from contact with the corrugated edge of the rail flange and the head of said spike is adapted to span 5 the joint between the corrugated edge of the abutment and the corrugated edge of the flange of the rail.

3. In combination with a rail having a base flange whose margin is formed other 10 than straight, a tie plate having rail-bearing elements for engagement and shaped to conform with the margins of the rail base flanges and there being a spike opening formed through the tie plate removed from 15 the engaging portions of a rail base flange and a rail bearing element a distance sufficient to cause part of the plate body to stand between the margin of the rail base flange and a spike driven through the opening in 20 the plate, but not a distance preventing the

head of the spike from overlapping the rail base flange.

4. A tie plate having a removable rail-bearing element upstanding from the rail seat of the plate and having a spike opening 25 formed through the rail-bearing element, laterally removed from the rail seat, whereby the rail-bearing element will prevent the base flange of a rail from engaging and wearing a spike seated in the opening, with 30 its head overlapping the base flange of the rail.

In testimony whereof, I have signed my name to this specification, in presence of two subscribing witnesses.

BENJAMIN B. BETTS.
